LAVATORY

Lee Kirk Watkins, Louisville, Ky., assignor to
American Radiator & Standard Sanitary Cor-
poration, Pittsburgh, Pa., a corporation of
Delaware

Application February 3, 1954, Serial No. 28,825

Term of patent 14 years

(Cl. D4—2)

To all whom it may concern:

Be it known that I, Lee Kirk Watkins, a citizen of the United States, residing at Louisville, State of Kentucky, have invented a new, original, and ornamental Design for a Lavatory, of which the following is a specification, reference being had to the accompanying drawing, forming a part hereof.

Figure 1 is a perspective view of a lavatory embodying my new design;

Figure 2 is a top plan view thereof on a reduced scale; and

Figure 3 is a side elevation thereof on a reduced scale.

The dominant features of the design reside in the portions shown in full lines.

I claim:

The ornamental design for a lavatory, sub-
stantially as shown and described.
